UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

DRAFT RIGGING.

Application filed June 28, 1924. Serial No. 722,919.

To all whom it may concern:

Be it known that I, DONALD S. BARROWS, a citizen of the United States, residing at Rochester, in the county of Monroe and State of New York, have invented certain new and useful Improvements in Draft Rigging; and I do hereby declare the following to be a full, clear, and exact description of the invention, such as will enable others skilled in the art to which it appertains to make and use the same.

The invention relates to draft rigging for railway cars and more particularly to improvements in cheek plates or stop castings having slots therein in which a key is received.

The principal object of my invention, generally considered, is to provide a cheek casting with means for compensating for wear so that travel of the cushioning elements of the draft rigging may be always maintained constant.

Still another object of the invention is to provide a cheek plate or stop casting having a key receiving slot therein with means adapted to contact the key to limit the movement thereof, said means being removable to permit of alteration in key travel or to compensate for wear in the cushioning elements.

To these and other ends, the invention comprises the various elements and combinations of elements as will hereinafter be more fully pointed out.

Before describing the invention in detail, it is believed that a clear understanding thereof may be had by a brief discussion of the problems involved. Practically all draft mechanisms are now connected to the coupler by means of a transversely extending key, the said key being adapted to be received in a slot in the coupler, aligned slots in the adjacent portions of the yoke, and the ends of the key extending within slots formed in the sills, which latter slots are generally reinforced by metallic elements surrounding the same, called cheek plates or stop castings. The slots in the sills are elongated so that on draft and buffing movements of the coupler the key is moved within the sill slots and the length of the sill slots is adjusted so that under buffing movements the key engages the rear end of the slots in the sills coincident with the closing of the cushioning unit. The

purpose of this construction is to distribute excessive loads above the capacity of the cushioning element or unit to a plurality of spaced points on the sills, some of which are preferably in line with the webs thereof. In service, however, the rear ends of the key slots in the sills or the adjacent edges of the key are often worn so that the entire load beyond the capacity of the cushioning unit is delivered directly to the same and not divided as above described, with the result that the cushioning unit is often seriously damaged.

In addition, all cushioning units do not have the same travel from open to closed position. In fact, cushioning units vary from one and three-quarter inches to three inches and consequently key slots which provide a three inch movement of the coupler key cannot afford any protection to a cushioning unit having less than three inches of closing movement, and it is to overcome these difficulties that the present invention was designed.

Referring now to the drawings:

Figure 1 is a view partially in plan and partially in section of a portion of a draft rigging of the well known Farlow two-key type.

Figure 2 is a side elevation of a sill showing a cheek casting applied thereof.

Figure 3 is a corresponding view but showing the exterior of the sill.

Figure 4 is a cross section on the line 4-4 of Figure 3, the direction of view being indicated by the arrows adjacent the ends of the section line.

Figure 5 is a section taken on the line 5-5 of Figure 3.

Figure 6 is a fragmentary sectional view taken on the line 6-6 of Figure 5, the direction of view being indicated by the arrows adjacent the ends of the section line.

The numeral 1 designates the center sills of a car to which are secured, by rivets or other suitable means, cheek plates or stop castings 2. 3 is the coupler, 4 the yoke, 5 a front follower, and 6 and 7, respectively, the coupler and follower keys. All of the parts, with the exception of the cheek plates 2 as will be hereinafter pointed out, are old and well known and their operation is so well understood that it is unnecessary to further describe the same.

The cheek plates 2 are each provided with

a plurality of longitudinally extending slots 8 and 9 in which are respectively received the keys 6 and 7. The slot 8 is elongated and extends on opposite sides of the key 6 so that the coupler key may move forwardly and rearwardly as necessary. The slot 9 is extended rearwardly of the key 7 in the normal position of the latter and the said key is in this position adapted to engage the wall 10 at the forward end of the said slot. The distance from the rearward edge of the keys 6 and 7 to the adjacent portions 11 and 12 of the respective slots is such that in the embodiment here illustrated the keys 6 and 7 will simultaneously engage the respective ends of their slots at the time the cushioning unit 13, diagrammatically illustrated by dot and dash lines, has closed. It will be observed that there is a clearance between the follower 5 and the forward edge of the key 7 so that in reality the slot 9 is of slightly less length than the slot 8 measured in both instances from the rear edge of the adjacent key. In order to provide for cushioning units of different closing movements and to compensate for wear, the portions which close the rear ends of the slots 8 and 9 are separable from the stop castings and are preferably formed as T-shaped members 14. Since the members 14 and the means by which these members are connected to the cheek plates is substantially identical, a description of one will suffice. At the rear edge of the slot 8 I provide a recess 15 which extends longitudinally of the cheek casting but is of less length than the bridge 16 which separates the front and rear slots. The slot 15 is intersected by an opening 17 through which a fastening means or rivet 18 may extend. Preferably, the side walls of the bridge 16 are provided with countersunk faces 19 to receive the head of the rivet or fastening means 18. The members 14 are adapted to engage the adjacent portion of the bridge 16 on opposite sides of the slot 15, as most clearly shown in Figures 1 and 5 of the drawings.

From the foregoing description it will be readily seen that the travel of the key or keys under buffing movements may be arranged to suit any type of cushioning unit by connecting to the cheek plate 2 a member 14 having the desired thickness, and that if the members 14 become worn due to the excessive buffing shocks, by substituting an-

other member or members of suitable thickness the travel of the key or keys may be readjusted so as to restore the parts to their original condition.

60

While I have illustrated and described my device in connection with a two-key type of draft rigging, it will be apparent to those skilled in the art that the device may be advantageously utilized in combination with a single key construction and that if desired, the parts 14 may be utilized at both ends of the slots so as to positively control the movement of the coupler under draft as well as buffing.

70

Having now described my invention, what I claim as new and desire to secure by Letters Patent, is:

75

1. In a draft rigging, the combination with slotted sills, of slotted cheek plates connected thereto, a key extending within said slots, and detachable means extending within said slots for limiting the movement of said key in one direction.

80

2. In a draft rigging, the combination with slotted sills, of slotted cheek plates connected thereto, a yoke, a key for connecting said yoke and sills, and removable means engageable with the end portions of said key for limiting the movement thereof in one direction.

85

3. In a draft rigging, the combination with slotted sills, of slotted cheek plates connected thereto, a slotted yoke, a key extending through said slots in said yoke for operatively connecting the same to said sills, and means positioned in said cheek plate slots for limiting the movement of said key in one direction.

90

4. In a draft rigging, the combination with slotted sills, of slotted cheek plates connected thereto, a key extending through said slots and adapted to operatively connect to said cheek plates a movable member of said draft rigging, said cheek plates being provided with means for engaging removable members, and removable members cooperating with said cheek plates, said last named members being adapted to limit the movement of said key in one direction.

95

5. A cheek plate for railway draft rigging provided with a slot, a wall of said slot having a recess therein, and a member fitting within said recess and adapted to reduce the length of said cheek plate slot.

100

In testimony whereof I affix my signature.
DONALD S. BARROWS.
